UNITED STATES PATENT OFFICE

2,397,365

APPARATUS FOR REVERSING FURNACES

Peer D. Nielsen, Lorain, Ohio, assignor to National Tube Company, a corporation of New Jersey

Application June 18, 1943, Serial No. 491,396

7 Claims. (CL 236—15)

This invention relates to apparatus for reversing a furnace of the regenerative type. In these furnaces air passes through regenerators where it is preheated and conducted to the fuel burners where it combines with the fuel to supply heat to the furnace. The burned gas passes out of the furnace on the opposite side thereof and through other regenerators where the heat from the waste gas is absorbed by the refractories in the regenerators. After an interval of time the direction of firing is reversed by shutting off the flow of fuel to the active burners and reversing the flow of air through the regenerators. A valve reversal system shuts off the flow of air to the first mentioned regenerators and initiates flow of air to the second named regenerators. At the same time flow of the waste gas is reversed. In order to keep combustion conditions within the furnace constant, these furnaces are often supplied with furnace pressure control systems. When fuel flow to the furnace is shut off, the furnace pressure diminishes and the pressure regulating damper starts to close to increase pressure to the value for which the regulating system is set. Momentarily in the reversing cycle of the air and flue gas dampers, both waste gas dampers are partially open, thus exhausting the furnace system from both ends and the pressure within the furnace proper is greatly diminished. This causes the pressure control system to further close the pressure regulating damper in an effort to maintain control pressure on the furnace. Since such pressure control systems have a tendency to overtravel the control point, the pressure control damper at this time is practically closed. Immediately following the complete reversal of the reversing dampers, the flow of waste gas from the furnace is necessarily completely reversed and the disturbance caused by the reversal of flow builds up a very high pressure in the furnace proper, thus causing the pressure control system to move the pressure control damper to a wide open position in an attempt to establish the desired control pressure. Application of fuel to the furnace is impossible until furnace pressure diminishes to a suitable level. As the pressure control system tends to overtravel the control position, the dampers close more than is necessary for establishing the control pressure after having been in a wide open position and as application of fuel would result in a further increase of furnace pressure, its application must be delayed until the "hunting" of the furnace control valve ceases. Thus, it will be understood that the disturbances to furnace pressures attending furnace reversal is

of such magnitude that the pressure control system cannot properly respond and the "hunting" set up by the control system in an attempt to keep up with the rapidly and widely changing pressure conditions is detrimental to furnace operation.

It is an object of this invention to prevent hunting of the furnace pressure control during reversal of the furnace.

10 Another object is to provide an interlock between the fuel supply and the furnace reversing system to prevent application of fuel to the wrong side of the furnace.

These and other objects will be more apparent 15 after referring to the following specification and attached drawings, in which:

Figure 1 is a schematic layout of the furnace reversing control system of the invention;

Figure 2 is a side elevation of the timer;

Figure 3 is an end elevation;

Figure 4 is a plan view thereof; and

Figure 5 is a view of the control panel.

Referring more particularly to the drawings, the reference numeral 2 indicates a regenerative 25 type furnace having burners 4 and 6 for supplying fuel to the furnace. The furnace shown is oil fired and the supply of oil to the burners is controlled by steam pressure operated valves 8 and 10. Atomizing steam is supplied to the burners

30 through pipes 12 and 14. Supply of steam to the burners and to the steam operated valves is controlled by solenoid operated valves 16 and 18. A double pole double throw switch 20 controls the energizing of the solenoids 16' and 18' of the

35 valves 16 and 18. A furnace damper reversal system 22 of common type is operated by means of reversal motor 24. A damper 26 in the flue 28 controls the furnace pressure, the position of the damper being varied by means of a piston 30

40 moving in cylinder 32 which constitute part of the furnace pressure control system. The furnace pressure control system which is of a well known type has an impulse line 34 running from a point outside of the furnace near the arch 45 thereof to one side of the diaphragm 36. A second impulse pipe 38 runs from the inside of the furnace to the other side of the diaphragm 36. Oil is supplied to the pressure control system through pipe 40. The position of movable jet 42

50 determines whether oil is to be supplied to the cylinder 32 through pipes 44 or 46. The operation of the pressure control system is as follows:

If the pressure within the furnace is greater than the control pressure, the pressure in impulse line 38 will force the diaphragm 36 to the right,

thus supplying oil to the pipe 46. This causes the piston 36 to move downwardly to open the damper 26. If the pressure in the furnace is less than 26. If the pressure in the furnace is less than the control pressure, oil will be supplied to the pipe 46 closing the damper 26, thus increasing the furnace pressure to that desired. Valves 48 and 50 in pipes 48 and 50 are operated by means of solenoids 48' and 50' respectively, to control the flow of oil to the cylinder 32.

In the furnace control system as shown in Figure 1, air is passing through regenerators 52 and fuel is being admitted through burners 4 while waste gas is passing out through regenerators 54. When it is desired to reverse the furnace, switch 20 is thrown to its neutral position. This de-energizes solenoid 16', thus closing steam valve 16. When the steam has been dissipated, the spring 56 closes valve 8, thus shutting off the flow of oil to the burner 4.

A second double pole double throw switch 58 is then thrown from the position shown to the left to make contacts 60 and 62. This closes the circuit to reversing motor 24 through conductors L₂, 64, 66, 68, contact 62, conductor 70, contact 72, conductors 74 and L₁. At the same time solenoid 76 is energized by the current flowing from the conductor L₂ through conductors 78 and 80 to conductor 68. This closes switch 82 causing the current to flow from conductor L₂ through conductors 78, 84, and 86, through coil 88 to conductor L₁. This lights the lamp 90 to show that the reversal motor 24 is operating. When coil 88 of relay 92 is energized the armature 94 of the relay moves upwardly to make contact 96 closing the circuit to synchronous clock motor 98. The synchronous clock motor rotates the cam 100 through gear 102 and pinion 104. On relay armature 94 is an arm 106 which is disposed to engage the periphery of the cam 100. A notch 108 is cut in the cam 100 and when engaged by the arm 106 causes the contacts 96 to be opened and contacts 110 to be closed by the action of the spring 112. With the arm 106 positioned at any other part of the periphery of the cam 100, contacts 96 are held in a closed position and contacts 110 in an open position. While the motor 98 is running, contacts 96 remain closed and solenoids 48' and 50' are deenergized, thus closing the valves 48 and 50 and holding the damper 26 in the position shown.

The motor 24 drives cams 114 and 116 which open and close contacts 118 and 12 respectively. The cams are so constructed and arranged that contact 12 will be open and contact 118 closed when the damper reversal is completed. The opening of contact 12 opens the circuit to motor 24, thus stopping the motor. At the same time solenoid 76 is deenergized, opening switch 82 and causing the light 90 to go out. After waiting a few seconds to permit flow of gases through the furnace to complete reversal and to permit exhaust gases to escape from regenerators 54, the switch 20 is thrown to the right making contacts 120 and 122. This causes the current to flow through conductors L₂ and 64, through solenoid 18', conductor 124, contact 120, conductor 126, contact 60 and conductors 128 and L₁, thus energizing solenoid 18' and opening steam valve 18. This causes steam to flow to the fuel valve 10 where it overcomes the force of spring 130, opening valve 10 and permitting oil to flow to the burners 6. Synchronous motor 98 and cam 100 are so constructed and arranged that the arm 106 falls into the notch 108 after sufficient time for pressure conditions in the furnace to become sta-

bilized. When the arm 106 is in the notch 108, contact 110 is closed which causes current to flow in conductor L₂ through contact 110, conductor 132, solenoids 48' and 50', and conductors 134 and L₁. The energizing of solenoids 48' and 50' opens valves 48 and 50, unlocking the pressure control and permitting normal operation of the control to resume.

Since the damper 26 is locked in position during reversal and until normal pressure conditions are established in the furnace, it will be seen that the objectionable hunting during reversal is eliminated. With switch 58 in its left hand position, air will flow through regenerators 54 and with the switch 58 in this position it is impossible to energize solenoid 16' regardless of the position of the switch 20. In like manner with the switch 58 thrown to the right, as shown in Figure 1, air will flow through regenerators 52 and it will be impossible to energize solenoid 18' regardless of which way switch 20 is thrown. This provides an interlock between motor 24 and the valves 16 and 18 which prevents application of fuel to the wrong end of the furnace.

When it is again desired to reverse the furnace, switch 20 is thrown to a neutral position shutting off the flow of steam to the burners, thereby stopping the flow of fuel oil and the switch 58 is thrown from its left hand position to the right hand position, closing the circuit to motor 24 through conductors L₂, 64, 66 and 68, contact 136, conductor 138, contact 118, and conductors 74 and L₁. The light 90 is lit, the timer set in operation and the pressure control is locked in fixed position. When the reversal of air flow is completed, contact 118 is open, stopping the motor 24, and the contact 12 is closed, thus preparing the control system for the next reversal. A push button switch 140 in conductor 142 is normally open but may be closed to operate motor 24 independently of the control system.

The switches 20 and 58, the light 90 and timer 144 may be mounted on a panel 146 in a convenient position. This enables the operator to determine the condition of the furnace at a glance.

While one embodiment of the invention has been shown and described it will be apparent that other adaptations and modifications may be made without departing from the scope of the attached claims.

I claim:

1. In a regenerative furnace having a motor for reversing the flow of air and flue gas through the regenerators and automatic pressure control, the combination which includes means for shutting off the flow of fuel to the burners, means for actuating said motor to reverse the flow of air and flue gas and simultaneously lock the pressure control in fixed position, means for supplying fuel to the burners on that side of the furnace to which air is being supplied, and means for unlocking the pressure control a sufficient time interval after reversal for pressure conditions in the furnace to become stabilized.

2. In a regenerative furnace having a motor for reversing the flow of air and flue gas through the regenerators and automatic pressure control, the combination which includes means for shutting off the flow of fuel to the burners, means for actuating said motor to reverse the flow of air and flue gas and simultaneously lock the pressure control in fixed position, means for supplying fuel to the burners on that side of the furnace to which air is being supplied, means for unlocking

the pressure control a sufficient time interval after reversal for pressure conditions in the furnace to become stabilized, and an interlock between the fuel supply means and the reversal motor to prevent application of fuel to the wrong end of the furnace.

3. In a regenerative furnace having steam operated valves for supplying fuel to the burners, a motor for reversing the flow of air and flue gas through the regenerators and fluid operated means for controlling the furnace pressure, the combination which includes means for stopping the flow of steam to the burners and thereby stop flow of fuel to the burners, a timer, means for starting the reversing motor and simultaneously setting the timer in operation to lock the pressure control in fixed position, and means for supplying steam to the burners on that side of the furnace to which air is being supplied, said timer operating to unlock the pressure control a sufficient time interval after reversal for pressure conditions in the furnace to become stabilized.

4. In a regenerative furnace having steam operated valves for supplying fuel to the burners, a motor for reversing the flow of air and flue gas through the regenerators and fluid operated means for controlling the furnace pressure, the combination which includes means for stopping the flow of steam to the burners and thereby stop flow of fuel to the burners, a timer, means for starting the reversing motor and simultaneously setting the timer in operation to lock the pressure control in fixed position, means for supplying steam to the burners on that side of the furnace to which air is being supplied, said timer operating to unlock the pressure control a sufficient time interval after reversal for pressure conditions in the furnace to become stabilized, and an interlock between the fuel supply means and the reversal motor to prevent application of fuel to the wrong end of the furnace.

5. In a regenerative furnace having steam operated valves for supplying fuel to the burners, a motor for reversing the flow of air and flue gas through the regenerators and fluid operated means for controlling the furnace pressure, the combination which includes a solenoid operated steam valve for controlling flow of steam to the burners on one side of the furnace, a second solenoid operated steam valve for controlling flow of steam to the burners on the opposite side of the furnace, means for deenergizing the solenoids to close the valves and stop flow of steam to the fuel valves and thereby stop flow of fuel to the burners, a timer, an electric circuit, cams driven by said reversing motor, means for closing said electric circuit to start said reversing motor and set the timer in operation to thereby stop the flow of fluid to the pressure control means, contacts in said circuit actuated by said cams, one of said contacts being broken when said air and flue gas reversal is completed to open said circuit to stop said reversing motor, and means for energizing one of said solenoids to open the fuel valves on one side of the furnace, said timer being constructed and arranged to permit flow of fluid to the pressure control means

a sufficient time interval after reversal for pressure conditions in the furnace to become stabilized.

6. In a regenerative furnace having steam operated valves for supplying fuel to the burners, a motor for reversing the flow of air and flue gas through the regenerators and fluid operated means for controlling the furnace pressure, the combination which includes a solenoid operated steam valve for controlling flow of steam to the burners on one side of the furnace, a second solenoid operated steam valve for controlling flow of steam to the burners on the opposite side of the furnace, a double pole double throw switch for controlling the energizing of said solenoids, a timer, an electric circuit, two cams driven by said reversing motor, two contacts in said circuit, each contact being actuated by one of said cams, the cams and contacts being so constructed and arranged that one contact is closed while the other is open, a double pole double throw switch in said circuit, said last named switch being adapted to close said circuit to start said reversing motor and set the timer in operation to thereby stop the flow of fluid to the pressure control means, one of said contacts being broken when said air and flue gas reversal is completed to open said circuit to stop said reversing motor, said switches being constructed and arranged so that fuel can be supplied only to the burners on that side of the furnace to which air is being supplied.

7. In a regenerative furnace having steam operated valves for supplying fuel to the burners, a motor for reversing the flow of air and flue gas through the regenerators and fluid operated means for controlling the furnace pressure, the combination which includes a solenoid operated steam valve for controlling flow of steam to the burners on one side of the furnace, a second solenoid operated steam valve for controlling flow of steam to the burners on the opposite side of the furnace, a double pole double throw switch for controlling the energizing of said solenoids, a timer, an electric circuit, two cams driven by said reversing motor, two contacts in said circuit, each contact being actuated by one of said cams, the cams and contacts being so constructed and arranged that one contact is closed while the other is open, a double pole double throw switch in said circuit, said last named switch being adapted to close said circuit to start said reversing motor and set the timer in operation to thereby stop the flow of fluid to the pressure control means, one of said contacts being broken when said air and flue gas reversal is completed to open said circuit to stop said reversing motor, said switches being constructed and arranged so that fuel can be supplied only to the burners on that side of the furnace to which air is being supplied, said timer being constructed and arranged to permit flow of fluid to the pressure control means a sufficient time interval after reversal for pressure conditions in the furnace to become stabilized.

PEER D. NIELSEN.
